CLAIM

The ornamental design for an intravenous pole adapter for support of a solution container, as shown and described.

DESCRIPTION

FIG. 1 is a perspective view of the intravenous pole adapter of the present invention shown affixed to a phantom partial perspective view of a pole;

FIG. 2 is a side view of the intravenous pole adapter of the present invention;

FIG. 3 is a top view thereof;

FIG. 4 is a side view thereof;

FIG. 5 is a front view thereof.

The broken lines are shown for illustrative purposes only.

FIG. 1

FIG. 2

FIG. 3

FIG. 4

FIG. 5
